UNITED STATES PATENT OFFICE.

ENSLEY C. SHEPHERD, OF MINERAL POINT, WISCONSIN.

WINDOW-SASH.

1,075,306.

Specification of Letters Patent.

Patented Oct. 7, 1913.

Application filed January 27, 1913. Serial No. 673,862.

To all whom it may concern:

Be it known that I, ENSLEY C. SHEPHERD, citizen of the United States, residing at Mineral Point, in the county of Iowa and 5 State of Wisconsin, have invented certain new and useful Improvements in Window-Sashes, of which the following is a specification.

This invention relates to window sashes. 10 One object is to provide a window sash embodying such characteristics that the glass panes may be held therein against rattling without the use of putty.

Another object resides in the provision of 15 a metallic window sash embodying such characteristics that it cannot be removed from the window casing from the outside of the dwelling or other place in which the window may be mounted.

20 Another object resides in the provision of a simple, inexpensive, durable and efficient window sash.

A still further object is to provide a window sash embodying among other characteristics means whereby the sash may have 25 free, easy and even sliding movement in the window casing and having means whereby weather strips are provided to prevent the ingress of air at the sides of the 30 casing from the outside.

With the above and other objects in view the invention consists in the construction and novel combination of parts, hereinafter more fully described, illustrated in the accompanying drawings and pointed out in the appended claim; it being understood 35 that various changes in the form, proportion, size and minor details of construction may be resorted to without departing from the spirit or sacrificing any of the advantages of the invention.

In the drawings:—Figure 1 is a face view 40 illustrating the lower window sash and a portion of the upper sash. Fig. 2 is a vertical sectional view. Fig. 3 is a horizontal sectional view. Fig. 4 is a horizontal sectional view of a modified form of the invention.

50 Referring now more particularly to the accompanying drawings, the reference character 10 indicates the casing in which the sashes are mounted, and in Figs. 1 to 3, inclusive, the casing has secured to the inner faces of its sides, strips 11, 12 and 13, each of 55 these strips being detachably secured to the casing by means of screws or other suitable

fastenings 14 so that the strips may be removed for purposes hereinafter explained. The strips 12 and 13 on opposite sides of the casing are spaced from each other to form 60 grooves 15 for the slidable reception of the outer metallic member 16 of the lower sash. This outer metallic sash member 16 is provided with a central opening 17. Between the glass and the outer and inner sash members 65 are disposed cushioning strips 18, 21, of felt, cork, paraffin paper, or other suitable material to cushion the pane and prevent its rattling.

The inner sash member, preferably in 70 the form of angle iron, has its web portion 20 arranged for coöperation with the outer sash member 16 to clamp the window pane 19 in the sash by means of the fastenings 25. The other web part 22 of the inner sash 75 member slides preferably against the outer face of the strips 12 and these strips are each provided with a notch 23 to form grooves between the strips 11 and 12 for 80 the slidable reception of the extended portions 24 of the inner sash member, which extended portions are directed outwardly into said grooves for the purpose of providing weather strips to prevent the ingress of cold air from the outside and also to provide for 85 a free, easy and even sliding movement of the outer sash member 16 in the grooves 15.

The window pane 19 may be of any suitable size but preferably does not extend to the marginal edges of the sash members 90 so that in clamping the panes between the sash members by means of the bolts, screws or other suitable fastening members 25, it is not necessary to penetrate the pane, as will be clearly seen in Fig. 3.

The strips 13 at the outer side of the casing are each provided with a notch 26 to slidably receive the weather strip wings of the upper sash. The outer sash member of the upper sash slides against the outer edge 100 of the strips 13 and when the upper sash is thus positioned, a finishing strip 27 may be secured to the outer face of the frame.

In practice, I preferably form the sash members of sheet or other light metal in 105 order that the sashes will be light to facilitate handling thereof when shipping the same or when removing them from the casings. In the particular instance illustrated in the drawings, it will be seen that the 110 sashes cannot be removed from the outside but must be removed, if it be desired to take

them out of the casings, from the inside. To remove the sashes from the casings, it would first be preferable to remove the lower sash and this may be removed from the casing by unscrewing or releasing the fastenings 14 of the strips 11 and 12 when the lower sash may be readily removed from the casing. To remove the upper casing, it is then simply necessary to release the 10 fastenings 14 of the strips 13, when the upper sash may be brought inwardly of the dwelling or other place where the window may be in use.

While I have described the method of removing the sashes from the casings, if desired, it will be understood that in order to remove the window pane of the lower sash, it is not necessary to remove both strips 11 and 12, because by removing the strips 11 15 and 12, the inner metallic sash member 20—22—24 may be readily disconnected from the outer sash member 16 by unfastening the fastenings 25.

From the foregoing, it will be seen that I 20 provide a compact metallic window sash, whose parts are few and which are arranged to provide an effectual clamping of the window panes in place against rattling without the use of putty.

25 The usual weight boxes 28 are shown in the drawings and it will be understood that weights (not shown) may be connected up with the sashes in any ordinary manner.

In Fig. 4 there is illustrated a modifica-

tion of the invention which is similar in all respects save that the inner angle iron sash members are not provided with the weather strip extensions 24 of Figs. 1 to 3, inclusive, and that consequently grooves for such weather strip wings are not necessary in the use of the structure shown in Fig. 4. In all other respects, both forms of sashes are the same.

What is claimed is:—

The combination with a window pane; of 45 elastic packing strips resting on the faces of said pane adjacent the edges thereof, a flat rectangular frame member having its sides projecting beyond the lateral edges and having portions overlapping the pane and resting on the packing on one side of said pane, a second frame member having its side portions Z-shaped in cross section, one leg of each side resting on the respective side portion of the remaining packing, the space 50 between the frame members at the outer edges of the latter being open and unrestricted, and fastenings passing transversely through the overlapping portions of said frame members and transversely of the pane 55 and spaced outwardly from the edges of the latter.

In testimony whereof I affix my signature in presence of two witnesses.

ENSLEY C. SHEPHERD.
